UNITED STATES PATENT OFFICE.

HARRY T. SHEARER, OF WAYNESBORO, PENNSYLVANIA, ASSIGNOR TO LANDIS TOOL COMPANY, OF WAYNESBORO, PENNSYLVANIA, A CORPORATION.

DIAMONDING-TOOL FOR GRINDING-MACHINES.

1,200,768.

Specification of Letters Patent.

Patented Oct. 10, 1916.

Application filed August 17, 1912. Serial No. 715,671.

To all whom it may concern:

Be it known that I, HARRY T. SHEARER, a citizen of the United States, residing at Waynesboro, Franklin county, and State of Pennsylvania, have invented and discovered certain new and useful Improvements in Diamonding-Tools for Grinding-Machines, of which the following is a specification.

My said invention consists in various improvements in the details of construction and arrangement of parts of diamonding tools for use in dressing the surfaces of grinding wheels, relating especially to tools adapted for dressing not only the faces, but the corners of said grinding wheels where it is desired to have such corners of a curved or convex character, whereby the radius of such a curve may be accurately determined as desired, all as will be hereinafter more fully described and claimed.

Referring to the accompanying drawings which are made a part hereof and on which similar reference characters indicate similar parts, Figure 1 is a side elevation of a tool embodying my said invention, Fig. 2 a detail view of a portion thereof on an enlarged scale, Fig. 3 a detail face elevation of the part shown in Fig. 2, Fig. 4 a detail section on the line of the diamond holder, Fig. 5 a cross section on the dotted line 5—5 in Fig. 2, and Fig. 6 a detail diagrammatic view.

In said drawings the portions marked A represent a work support, or base, on which said diamonding tool is mounted, B the frame of said diamonding tool, C the support of said diamonding tool, and D the diamond point.

The work rest A is shown merely to illustrate the support on which the diamonding tool is commonly used and requires no special description, inasmuch as it forms the subject matter of another application filed April 5, 1912, Serial Number 688,652.

The frame B is a casting of appropriate form to support the diamonding tool mechanism and is preferably mounted on the top of the frame A and secured thereon by inter-engaging parts and clamping bolts b, or in any appropriate manner. It will be understood, of course, that said diamonding tool may be mounted directly upon the work carriage of the grinding machine if preferred and provided with a frame suitable for such mounting.

The support C is a casting designed especially to carry the diamond holder and is formed with a journal a on its upper end which is mounted in a bearing b on the upper end of frame B. A lever 10 is secured to the upper end of said journal by which said support may be swung on said journal. Stop screws 11 are mounted in the face of the upper end of bearing b to limit the movement of said lever 10 to swing the diamonding tool through the arc of a circle of a length required by the work. An anti-friction roller 12 is carried by a screw 13 on the lower end of said support C adapted to bear against the inner face of a track 14 formed on the arc of a circle on the lower end of frame B thus affording a support for said lower end while permitting it to swing to carry the tool in the arc desired. Said support C is formed with a transverse slot c with parallel projecting arms 15 on each side thereof through which a set screw 16 extends for the purpose of springing said support to force roller 12 solidly against track 14 and make support C rigid, as will be readily understood.

The diamond D is mounted in a holder d which is secured by a set screw 17 in a socket in the inner end of a screw rod 18 which is connected by a screw-threaded connection with the front end of a sleeve 19 mounted in a transverse perforation near the lower end of said support C. A knurled wheel 20 is mounted on the outer end of said screw 18 by which it may be turned for adjustment in said sleeve 19, and a jam nut 21 is mounted thereon to secure it in the adjusted position. Said sleeve 19 is secured against longitudinal movement by a set screw 22 inserted in a perforation in the side of support C and engaging with a groove g in the periphery of said sleeve. The perforation in said sleeve 19 in which said screw 18 is mounted is formed eccentric thereto as shown in Fig. 5, so that by turning said sleeve the diamond D may be readily brought to the exact center in line with the axis of the journal a of said support C so as to turn on a true arc of a circle in rounding the corners of the grinding wheels.

Thus far the tool described is of a type hitherto in use in connection with the "Landis" grinding machine and is shown and described to give a clear understanding of my improvement, which constitutes my

present invention, and which will now be described.

Alongside screw 18 and parallel therewith is formed another perforation in a wing 23 5 on support C in which is mounted a sliding rod 24 which is adapted to be secured in any position by means of a set screw 25 adapted to impinge against its side. On its forward end is mounted an arm 26 extending at right angles and secured to turn therewith by a pin 27. The outer face of wing 23 is flattened and formed with a slot s along the edges of which are formed scales as best shown in Fig. 2, an indicator mark x being 10 formed on the side of rod 24 to register therewith. The outer face of wing 23 is preferably flattened along the side of said slot s in order that the scale along the edges of said slot may have a sharp edge to better 15 register with said indicator mark x. I have utilized both edges in order to have both the English and metric systems provided for use as may be preferred in the locality where the machine is being used. Said scale is designed to determine any radius which will 20 be described by the inner face of its arm 26 on the turning of support C on its journal by lever 10. By this means the corners of 25 the grinding wheel W may be ground of the exact radius desired as follows: The curve 30 desired for the corners being determined, said arm 26 is set across the path of diamond D as indicated by dotted lines in Fig. 3, at the position where the scale will indicate the 35 radius of said curve. The rod 24 is then locked in this position by means of the set screw 25 and the screw rod 18 adjusted to bring the diamond D against the inner face 40 of said arm 26 in which position it is locked by the jam nut 21. Said screw 25 is then loosened and arm 26 allowed to fall to the 45 position shown by whole lines in Fig. 3 which is its normal position, and rod 24 may be slid back to bring the parts out of the way of the work.

In operation the grinding wheel is set to move across the path of the diamonding tool or the diamonding tool may be carried on a part set to move across the face of said 50 grinding wheel. The grinding wheel being in rapid rotation the face is dressed off squarely and truly by the tool manipulated by the handle 10 which is set in position to support the tool to carry it parallel with 55 the axis of said grinding wheel. When the corners of the grinding wheel are to be rounded, as indicated in Fig. 6, the tool will be turned by the handle 10 as it reaches said

corners and, the radius having been determined and fixed, said diamond will pass over said corners on the exact arc or curvature desired. The operation continues back and forth until the face is dressed truly, including the corners, when the tool is removed or adjusted out of position by being slid rearwardly on the supporting ways at the upper end of frame A.

Having thus fully described my said invention what I claim as new and desire to 70 secure by Letters Patent is:

1. In a diamonding tool for grinding machines, the combination of a frame, a pivoted support carried by said frame, an adjustable diamond holder mounted in said 75 pivoted support, and a radius finder mounted alongside said diamond holder comprising a sliding rod mounted parallel with said diamond holder and carrying a right angular arm adapted to swing across the 80 path of the diamond point, a scale being provided on one part and an indicator on the other for determining the radius, and means for securing said rod in the desired position, substantially as set forth. 85

2. In a diamonding tool for grinding machines the combination of a frame, a pivoted support for the diamond holder carried by said frame, means for swinging said support in said frame, a diamond holder carried in a socket in said support, means for adjusting and securing said holder, and a radius finder mounted on said support alongside said diamond holder comprising a sliding part with an arm adapted to swing 90 across the diamond point or out of the way thereof, a scale being formed on one part and an indicator on the other for determining 95 said radius, substantially as set forth.

3. A radius finder for diamonding tools 100 for grinding machines comprising a swinging support, a diamonding tool carried by said swinging support, and a sliding part mounted alongside said diamonding tool provided with a scale for determining the 105 radius, and means for fixing said diamonding tool by said sliding part, substantially as set forth.

In witness whereof, I have hereunto set my hand and seal at Waynesboro, Pennsylvania this 29th day of July, A. D. nineteen hundred and twelve.

HARRY T. SHEARER. [L.S.]
